HARRY A. SCHADE, OF EAST CLEVELAND, AND FRANCIS N. RICHARDSON, OF CLEVELAND, OHIO.

ELECTRIC-SPARK-DISCLOSING MEANS FOR INTERNAL-COMBUSTION ENGINES.

1,172,168.

Specification of Letters Patent.

Patented Feb. 15, 1916.

Application filed April 9, 1910. Serial No. 554,537.

To all whom it may concern:

Be it known that we, HARRY A. SCHADE and FRANCIS N. RICHARDSON, citizens of the United States, residing at East Cleveland and Cleveland, respectively, in the county of Cuyahoga and State of Ohio, have invented certain new and useful Improvements in Electric-Spark-Disclosing Means for Internal-Combustion Engines, of which 10 the following is a specification.

Our invention relates to means for visually disclosing the effect of the passage of an electric current through a portion of its circuit, and is adapted especially to be 15 used with internal combustion engines using electrical ignition devices, all substantially as shown and described and particularly pointed out in the claim.

In the accompanying drawings, Figure 1 20 is a side elevation of a portion of a four cylinder machine with our invention installed therein, as hereinafter fully described. Fig. 2 shows a series of four vacuum tubes located side by side upon a suitable back support, and Fig. 3 is a cross section of Fig. 2 upon line α — α . Fig. 4 is a perspective view of one of the combined clamp and terminal members used with each of the several vacuum tubes at their respective ends, 30 and Fig. 5 is a perspective view of one of the vacuum tubes alone.

The object of the invention is to provide means whereby failure of any one of the 35 sparking devices for the several engine cylinders will be instantly disclosed to the observation of the driver or operator of the machine and also the particular engine cylinder wherein the defect occurs, so that the trouble may be remedied without further 40 confusion or delay.

Heretofore in machines employing one or more engine cylinders if sparking should fail in any one of them it was difficult to locate the particular one wherein the failure 45 occurred and it was necessary to stop the machine and make personal tests and examinations from cylinder to cylinder to locate the trouble before the remedy could be applied. By the present invention we are 50 enabled to detect any failure of sparking in any cylinder the instant such failure occurs and also to locate exactly the particular cylinder involved, and all this is accomplished by a series of vacuum tubes arranged successively in the sparking circuits of the sev-

eral cylinders or engines and which are openly transparent and exposed immediately in front of the operator upon the dashboard or in some other convenient position so as to be observed without effort. 60

Now, pursuing the foregoing conception into the mechanism of the case, the characters A, B, C and D, respectively, represent say four several explosion cylinders or engines of what is known as a four cylinder 35 machine. It might be one or more cylinders for that matter, and whatever the number of cylinders the operation is the same as to each one, so that the case may be simplified by describing the electrical mechanism or 70 circuit as it relates to a single cylinder. Thus, each cylinder has one of the several vacuum tubes operatively associated therewith, and which are numbered 1, 2, 3 and 4, respectively, corresponding to the four several cylinders, A, B, C and D, and it may be assumed that tube 1 has operative connection with cylinder A. These tubes are preferably provided with a relatively small quantity of mercury or its equivalent to promote a better flow of the electric fluid in 80 vacuum and cause a brighter illumination than if the mercury were omitted, and have electric terminals a and b in their respective ends constituting, in this instance, portions 85 of the conducting bands or caps 5 upon the outside of said tubes. The tubes themselves are made of transparent glass, so that any light within the same will be plainly observable to one who occupies a seat in the 90 machine and have inwardly projecting nipples n at their ends in which the said terminals a and b are supported. This also provides an inside pocket for the mercury as shown at m . It should be understood, how- 95 ever, that the invention does not necessarily call for a mercury tube but comprises a vacuum tube or member regardless of the presence of mercury or other conducting substance or medium therein, as such vacuum tubes alone will glow as the current travels through vacuum between the two points a and b .

Now, having the several tubes arranged for example as they appear in Fig. 2, they 105 are fixed in position upon a special board or backing E in this instance by means of the clamping and terminal brackets G affixed to the said backing by screws or any suitable means. Each of said brackets has 110

a pair of spring metallic clamps or jaws 6 adapted to engage about the cap on the corresponding end of the tube, and it is a matter of a moment's effort to spring a tube into 5 place or remove it from its clamps. Headed screws 7 in said brackets serve as terminals or means for engaging the wires of the circuit, and the line of travel of the current from the source of energy or supply is 10 through these terminals and through the vacuum in the tube by way of points *a* and *b* to the sparking devices upon the cylinders. Any suitable source of energy may be employed whether it be a battery or other well 15 known generator, and in Fig. 3, the circuit is traceable along the line of connections indicated by 8 from the battery 15. It should be further understood that we can use a vacuumized or partially vacuumized 20 tube or one containing gas, vapor or other fluid possessing the electric conducting properties and in that case forming an integral part of or continuous with an electrical circuit or system and which constitutes the 25 ignition system of an electrically fired and discharged hydrocarbon engine and otherwise known as an internal combustion engine. The presumption of course is that any such gas, vapor, or fluid in said tubes must 30 possess the property of becoming illuminated during the passage of electrical current through the same.

For the purposes of this description the terminal points 18 on the respective cylinders may be regarded as representing the igniters or sparking devices herein referred 35 to, and 10 represents a spark coil. The back plate or board E carrying the vacuum tubes is shown as having an opening 12 behind 40 said tubes and a corresponding opening 16 is provided in the dashboard J, thus providing for observation on the tubes 1 from behind as well as in front of the machine. This is important to enable the person who 45 is making repairs or tests at the engines to see which tube responds and which fails, so that it is very material in a device like this to have the said openings so that said observations can be made. We show transparent 50 tubes but use the said word tube in the sense of a transparent part or bulb as it might

have a different shape or be otherwise than tubular and serve our purpose. It is in this sense that the term is used in the claim.

Respecting the use of the vacuum tubes 55 in an electric circuit as herein described we may add that we have carefully tested out the effect of the said tubes in the circuit by means of a hot wire ammeter, and the test showed a higher reading in amperes with 60 the said tubes than without them, the reason probably being that the tubes operate more or less as condensers with obvious advantage at the spark plug.

Although this invention is herein described in connection with automobiles, it is not necessarily limited thereto, but may be used wherever internal combustion engines, or sparking circuits are employed, say as in launches or even stationary engines. 65

A cut-out switch for each tube may be used in the electrical circuit of each, thereby permitting a continuous metallic circuit to be established in the event that any tube is broken or out of commission. However, it 75 is also plain that any metallic piece, such as a wire or short metal bar may be seated between any pair of opposed contacts 6 when the tube is removed or even when still in place to short circuit that particular tube. 80

What we claim is:

Electric spark disclosing means for internal combustion engines comprising a transparent vacuum tube for each engine having a barrel-shaped body and relatively 85 reduced ends provided each with an inwardly projecting nipple and electric terminals through said nipples, caps of conducting material sleeved upon said ends and provided with said electric terminals at their 90 middle, the said tubes being constructed alike at both ends and reversible as to their ends and the said terminals terminating in the respective ends of the tube.

In testimony whereof we affix our signatures in presence of two witnesses.

HARRY A. SCHADE.
FRANCIS N. RICHARDSON.
